UNITED STATES PATENT OFFICE

145,086

DESIGN FOR AN AIRPLANE

Volmer S. Jensen, Glendale, Calif., assignor to
Jarvis Manufacturing Company, Glendale,
Calif., a corporation of California
Application October 12, 1945, Serial No. 122,808

Term of patent 14 years

(Cl. D71—1)

To all whom it may concern:

Be it known that I, Volmer S. Jensen, a citizen of the United States, residing at 1010 Mariposa Street, Glendale, county of Los Angeles, State of California, have invented a new, original, and ornamental Design for Airplane, of which the following is a specification, reference being had to the accompanying drawing, forming part thereof.

Fig. 1 is a perspective view of an airplane showing my new design as it would appear during flight;

Fig. 2 is a top plan view with portions of the wing broken away from convenience of illustration; and

Fig. 3 is a side elevational view thereof.

The side of the airplane opposite to that shown in Figs. 1 and 3 is the same except for the fact that the door shown in Figs. 1 and 2 does not appear on the other side.

I claim:

The ornamental design for an airplane, as shown and described.

VOLMER S. JENSEN.
